UNITED STATES PATENT OFFICE.

JESSE COATES, OF LYNN, MASSACHUSETTS, ASSIGNOR TO GENERAL ELECTRIC COMPANY, A CORPORATION OF NEW YORK.

TRANSFORMER.

No. 873,721.

Specification of Letters Patent.

Patented Dec. 17, 1907.

Application filed February 12, 1906. Serial No. 300,594.

To all whom it may concern:

Be it known that I, JESSE COATES, a citizen of the United States, residing at Lynn, county of Essex, State of Massachusetts, have invented certain new and useful Improvements in Transformers, of which the following is a specification.

My present invention relates to stationary electrical transformers of the type such as is shown in the patent to Hall, No. 755,766, in which all of the windings of the transformer surround a central core-leg of magnetic material, the ends of the core-leg surrounded by the windings being connected by a number of return circuits of magnetic material which pass around the outer surface of the windings.

My invention comprises certain improvements in the configuration and production of the core blank laminae, their assembly to form the transformer core, and the arrangement of the coöperating windings with respect thereto.

The various features of novelty which characterize my invention are pointed out with particularity in the claims annexed to and forming part of this specification. For a better understanding of my invention, however, reference may be had to the accompanying drawings and descriptive matter, in which I have illustrated and described forms in which my invention may be embodied.

Of the drawings, Figure 1 is a perspective view illustrating a transformer constructed in accordance with my invention; Fig. 2 is a sectional plan view of the transformer shown in Fig. 1; Fig. 3 is a view similar to Fig. 2, showing a modified construction; Fig. 4 is a view illustrating the method of cutting out certain of the transformer core blanks; Fig. 5 is a view of one of the main **E** punchings and coöperating end-closing members; Fig. 6 shows the punching of Fig. 5 reversed; Fig. 7 shows one of the main **U**-punchings and end-closing member; Fig. 8 shows the other main **U**-punching and end-closing member; Figs. 9 and 10 correspond to Figs. 7 and 8, and illustrate another pair of **U**-punchings and connecting members; Figs. 11 and 12 also correspond to Figs. 7 and 8, and illustrate a third pair of **U**-punchings and connecting members; and Figs. 13, 14 and 15 are views similar to Fig. 2, each showing a modified arrangement.

Referring first to the construction shown

in Figs. 1 and 2, the transformer core is composed of a bundle 1 of **E**-punchings and suitable end-members, two main bundles 2 of **U**-punchings extending from opposite sides of the middle leg of the bundle 1 and co-operating end-members, auxiliary bundles 3 of **U**-punchings and end-members arranged one at each side of the bundles 2 and other auxiliary bundles 4 of **U**-punchings and end-members also arranged one at each side of each set of punchings 2.

The laminae composing the bundles 2 and 3 are parallel to each other and at right angles to the laminae of the bundles 1 and 4.

It will be observed that the transformer core comprises a central leg 5 about which is placed the high-voltage windings 6 and the low-voltage windings 7 of the transformer. The central leg of the transformer comprises the middle leg of the bundle 1 and the smaller leg portions of the bundles 2, 3 and 4. Without the windings of the transformer are located two legs 6', similar to each other, and two other legs 7', which are similar to each other. The legs 6' and 7' are parallel to the center leg 5. The ends of the outer legs are connected to the ends of the leg 5 by end connections 6'' and 7'', respectively. Each leg 6' consists of the wider leg portion of one bundle 2 and the wider leg portions of two bundles 3. Similarly, each leg 7' consists of an end-leg of the bundle 1 of **E**-punchings and the wider legs of two bundles 4. The bundles 1 and 4 may be secured together by pins of insulating material (not shown). Similar pins may be employed for securing together the adjacent bundles 2 and 3.

While the punchings composing the core may be proportioned with respect to each other in various ways to meet the conditions of particular designs, I prefer in some instances to form the **E**-punchings 1' of the bundle 1, and the **U**-punchings 2' and 2'' of the bundles 2, as indicated in Figs. 4 to 8, inclusive.

Referring first to Fig. 4, it will be observed that I form one **E** punching 1' and two **U**-punchings 2' and 2'' and two end-closing members 11 and two end-closing members 12 from stock material with a waste of only the three small portions 13. Figs. 5 and 6 illustrate how the two magnetic circuits of the punchings 1' are completed by the end-closing members 11. It will be understood that the punchings shown in Figs. 5 and 6

are identical in configuration, the only difference being that the punchings in one figure are reversed with respect to those in the other. Those skilled in the art will understand that in forming the bundle 1 of these punchings some of the superimposed punchings are arranged as shown in Fig. 5 with respect to the bundle, while others are arranged as shown in Fig. 6, thus breaking joints.

The U-punchings 2' and 2'', shown in Figs. 4, 7 and 8, differ from each other in that the punching 2' has the free ends of its legs beveled in one direction, while the punching 2'' has the free ends of its legs beveled in the opposite direction. The two members 12 are similar to each other and serve as end-closing members for the punchings 2' and 2''. It will be understood that the punchings 2' and 2'' are made dissimilar in order that in the assembled punchings the joints may be broken.

By making the ends of the spaces in the punchings 1', 2' and 2'' of the form shown in Figs. 4 to 8, inclusive, the magnetic circuit is shortened slightly. That the corners are cut off of the space between the legs is not a disadvantage, since it permits the primary windings, which are located between the secondary windings, to be made longer than the secondary windings, which is an advantage, or permits the use of a more effective insulation between the ends of the primary windings and the core or permits a combination of these advantages. This feature is clearly illustrated by the dotted arrangement of coils shown in Fig. 5.

By making the end-closing members 11 and 12 with one abutting edge 14 parallel to the sides of the core-legs and the other 15 inclined thereto, with a corresponding arrangement of the ends of the core-legs, the assembly of the end-closing members, which takes place after the remainder of the core is assembled and the windings are put in place, is facilitated, since, when the end-closing members are forced home, the edges of the end-closing member and abutting edges of the co-operating core-legs are wedged together thus forming good joints. With this construction less trouble on account of scratched plates and electric short-circuits between adjacent laminæ produced by fins or projections from the laminæ is experienced than when the joints are parallel to and at right angles to the length of each end iron or connecting piece. Moreover the arrangement of bevel joints with the joints of adjacent laminæ reversed as shown, results in less core loss at the joints than with the construction in which the joints are parallel to and at right angles to the length of the end irons or connecting members. This is because the unbroken or unjointed iron at the side of each joint in the construction with

the bevel joints is less than in the other construction, thus increasing the resistance to and reducing the extent of the eddy currents resulting from the flux which passes from one laminæ into a laminæ at the side thereof. It will be understood that a large portion of the flux instead of passing directly from the leg of a U-punching for instance into the corresponding end iron or connecting piece through the joint between them passes first out of the leg laterally into an adjacent punching lapping the joint and then laterally back into the end iron. This is on account of the relatively large areas of the air-gaps between the leg and adjacent laminæ and adjacent laminæ and end iron.

The material 16 cut off of the corners of the outer legs of the E-punching and off one corner of the wide leg of each punching 2' and 2'' is not detrimental, since the position of the material clipped off renders it practically ineffective. Similarly, the spaces 17 formed in the middle leg of the punching 1 do not injuriously affect the magnetic properties of the transformer core. Punchings 3' and 3'', 4' and 4'', forming the bundles 3 and 4', respectively, are similar respectively to the punchings 2' and 2''. Their co-operating end-closing members 18 and 19, respectively, are similar to the end-closing members 11 and 12.

In the construction shown in Figs. 1, 2 and 4 to 8 inclusive, the wide legs of the punchings 2' and 2'' are each equal in width to each narrow leg of the E-punchings 1 and each space between the narrow and wide legs of the punchings 2', 2'' and 1'. Similarly, the yoke portions of the U-punchings 2' and 2'' and the yokes connecting the narrow and wide legs of the punchings 1' are each equal in width to the spaces between the narrow and wide legs. The wide leg of the punching 1' is twice as wide as each narrow leg of the punching. The narrow legs of the punchings 2' and 2'' are each about two-thirds as wide as the wide legs of these punchings.

Referring to Fig. 2, it will be observed that the width of each bundle 2 is equal to the width of the bundle 1. This permits an economical use of material, since there are twice as many punchings 2' and 2'' formed from stock by the method illustrated by Fig. 4 as there are of punchings 1' so formed.

The construction described permits of a very economical use of material. By subdividing the magnetic circuit of the core, its mean length is reduced, thus reducing the quantity of iron necessary. By arranging the windings so that they surround only one portion of the core, and then making the portion of the core surrounded practically circular in outline, the mean length of turn of conductor is made small for the amount of magnetic material surrounded and the total amount of conducting material employed in

a transformer of a given rating is made less than has heretofore been employed in transformers in general use. The transformer construction described, therefore, permits 5 not only of the use of a small amount of material, but also permits the proportion of the conducting material, such as copper, to the iron employed to be small. This, of course, is an advantage, since the conducting material, 10 ordinarily copper, costs several times as much as does a similar weight of iron.

The mechanical construction of the core described is good. The bundle of **E**-punchings forms a rigid member to which the remaining 15 portion of the core may be mechanically connected in any suitable manner. The arrangement of the bundles permits the central leg to be made substantially circular in outline, with the use of a comparatively few styles and sizes of punchings.

In order to prevent an undue amount of cross-flux in the central leg passing from one bundle into another, the ratio of the part of each bundle forming a portion of the central leg to the part forming a portion of an out leg should be practically uniform in the various bundles. As shown, the outer leg portions of the bundles 2, 3 and 4 are wider than the corresponding central leg portions 25 of the bundle in about the same proportion, while the outer legs of the **E**-punchings are together equal in width to the central leg of the **E**-punchings. In order to preserve the proportion above referred to, I have increased the cross-sectional area of the legs 30 by interleaving between some of the portions of the **E**-punchings forming a part of the legs extra laminæ of magnetic material, thus increasing the dimension of the legs in 35 a direction at right-angles to the planes of lamination.

In separating the laminæ in the manner indicated in Fig. 4, any suitable cutting mechanism may be employed, for instance, a continuously 45 acting roller cutting die may be used.

In the form of my invention shown in Fig. 3 I have shown an arrangement of the bundles 1₁, 2₁, 3₁ and 4₁, which gives a section of the central leg 5 of the core such that the proportion 50 of the length of the coil surrounding the core to the cross-sectional area of the core surrounded is even higher than with the construction shown in Figs. 1 and 2, and closely approximates the condition in which 55 the core and coil are truly circular. The bundles 1₁, 2₁, 3₁, and 4₁ may be made up as in the form of my invention first described, or may be built up of laminæ assembled in 60 any well-known manner.

In the form of my invention shown in Fig. 13 bundles of laminæ 20, 21, 22 and 23 are employed corresponding to the bundles 1, 2, 3 and 4 respectively of Figs. 1 and 2. In 65 this form of my invention, however, the bun-

dles 22 and 23 are formed of punchings of the same size, thus reducing the number of sizes of punchings necessary. This advantage is also possessed by the construction shown in Fig. 14 in which the bundles of punchings 24, 70 25, 26 and 27 correspond to bundles 1, 2, 3 and 4 respectively of Figs. 1 and 2, and in which the bundles 26 and 27 are formed of punchings of the same size.

In the construction shown in Fig. 15, bundles of punchings 28, 29, 30 corresponding to the bundles 1, 2 and 4 respectively of the construction shown in Figs. 1 and 2 are employed; there being no bundles corresponding to the bundles 3 of the construction of Figs. 1 and 2.

While the particular forms of my invention hereinbefore described and illustrated possess many excellent properties, it will be readily understood by those skilled in the art that changes may be made in the forms disclosed without departing from the spirit of my invention, and that some features of my invention may in some cases be used without a corresponding use of other features; and I do not wish the claims herein-after made to be limited to the particular embodiments disclosed more than is made necessary by the state of the art.

What I claim as new and desire to secure by Letters Patent of the United States, is,—

1. In a transformer, a core portion comprising a pair of parallel legs one leg having the corner of one end adjacent the other leg beveled off, and a connecting member having one end beveled off and engaging the beveled end of the said one leg, the other end of said member being parallel to and abutting against the side of said other leg.

2. In a magnetic core, a main body of 105 magnetic material laminated in one direction, two other main bodies of magnetic material laminated transversely to the first-mentioned body and located one at each side thereof with the edges of their laminæ abutting against the end laminæ of the first-mentioned main body, the laminæ composing the first-mentioned main body being wider than the sides of the other bodies abutting against it, and one or more bodies 110 of magnetic material composed of laminæ parallel to the laminæ in one of said main bodies located in the corner spaces between the first-mentioned main body and each of the said two other main bodies.

3. A transformer core comprising a central leg made up of the middle leg of a main bundle of **E**-shaped laminæ and of one leg of each of two main bundles of **U**-shaped laminæ extending transversely to the **E**-shaped laminæ from opposite sides of said middle leg and one leg of one or more other bundles of **U**-shaped laminæ each of which is adjacent and laminated parallel to one of said main bundles.

4. The method which consists in forming an **E**-punching having its middle leg wider than its outside legs, two substantially similar **U**-punchings one leg of each of which is equal in width to the space between the wide leg and either narrow leg of the **E**-punching, and the necessary end-members, which consists in cutting from stock equal in width to the length of the legs of the **E**-punching plus twice the width of a narrow leg of the **E**-punching a **U**-shaped punching from the material surrounding each narrow leg of the **E**-punching and forming the end-members for the **U**-punchings by cutting a portion off of the free ends of the legs of the **U**-punchings remote from the center leg of the **E**-punching and forming the end members for

the **E**-punching out of material cut from the free end of the middle leg of the **E**-punching.

5. In a transformer, a pair of parallel core 20 portions and a transverse connecting portion, fillets in the corners between said connecting portion and each parallel portion, and windings in the space between said core legs, said windings comprising low potential conductors 25 adjacent each parallel portion and intermediate high potential windings.

In witness whereof, I have hereunto set my hand this 7th day of February, 1906.

JESSE COATES.
